Term of patent 14 years

(Cl. D52—3)

FIG. 1

FIG. 3.

FIG. 2.

FIG. 4.

FIGURE 1 is a perspective view of a vending machine embodying our new design;

FIG. 2 is a front elevation of the lighted panel forming a part of the vending machine; and

FIGS. 3 and 4 are sectional views taken on the lines 3—3 and 4—4 of FIG. 2.

The opposite side of the vending machine is substantially the same in appearance as the side shown, and the rear is unornamented.

The dominant features of the design reside in the portions shown in full lines in the drawings.

We claim:

The ornamental design for a vending machine, substantially as shown and described.
